FIG. 1

FIG. 2

FIG. 4

FIG. 3

FIG. 5

Figure 1 is a side elevational view of an aircraft, showing my new design thereof, the wings and propellers being disposed in position for vertical ascent, descent and hovering of the aircraft;

Figure 2 is a similar view but showing the wings and propellers in position for horizontal takeoff and flight;

Figure 3 is a top plan view of the craft as it appears in Figure 2;

Figure 4 is a front elevational view thereof as it appears in Figure 2; and

Figure 5 is a front elevational view thereof as it appears in Figure 1.

I claim:

The ornamental design for an aircraft, substantially as shown.
